UNITED STATES PATENT OFFICE.

ELLIS F. EDGAR, OF WOODBRIDGE, NEW JERSEY.

ROCKING GRATE.

SPECIFICATION forming part of Letters Patent No. 732,722, dated July 7, 1903.

Application filed January 28, 1901. Serial No. 44,775. (No model.)

To all whom it may concern:

Be it known that I, ELLIS F. EDGAR, a citizen of the United States, and a resident of Woodbridge, in the county of Middlesex and State of New Jersey, have invented certain new and useful Improvements in Rocking Grates, of which the following is a specification.

Figure 1 is a plan view of a grate, illustrating my invention, part complete and part with rectangular grate-sections removed to show shaking system. Fig. 2 is a side elevation of Fig. 1, part in full and part in section. Fig. 3 is a plan view of one of the rectangular grate-sections. Fig. 4 is a side elevation of one of the rectangular grate-sections, part in full and part in section. Fig. 5 is an end elevation of one of the rectangular grate-sections, part in full and part in section. Fig. 6 is an end view of a T-girder. Fig. 7 is an end view of an L-girder. Fig. 8 is a plan view showing center T-girder 14, bearing-bars 12, and end girders 12'.

The novelty in this grate lies in the construction of the rectangular grate-section, (shown in Figs. 3, 4, and 5 in detail,) frame 1, short grate-bars 5, combination grate-bar and shaking-arm 4, strengthening and supporting bar 2, offset shoulder 3. A frame made in this manner will expand and contract without cracking and I have found to be very durable. In a very long fire-box I have found it of great advantage to fire from each end and to operate the shaking of the grate-sections from each end. In that case the grate-bearing bars 12 are supported on the outside in girders 12', as shown in Figs. 1 and 2; but as it would not do to have bearing-bars 12 run the whole length of a long furnace, as they would warp and crack with the weight in the center, so I would have them go only half the length and have a girder 14, an end view of which is shown in Fig. 6, run across the center of the furnace for supporting bearing-bars 12. In the center of the furnace

this girder 14, end view in Fig. 6, is made on both sides of suitable shape for supporting bearing-bars 12, as shown in Fig. 8.

Having described my invention, what I claim as new, and wish to secure by Letters Patent, is—

1. A grate-bar comprising a strengthening-bar provided at its ends with suitable journals, a fuel-supporting grate formed integrally with and supported from said bar at the ends thereof, said grate being spaced from said bar intermediate its ends and comprising longitudinal side bars and transverse grate-bars connecting said longitudinal side bars and spaced from one another, and a shaking-arm formed integrally with the strengthening-bar and extending above the same to provide a fuel-bearing surface, substantially as set forth.

2. A grate-bar comprising a strengthening-bar provided at its ends with suitable journals, a fuel-supporting grate formed integrally with and supported from said bar at the ends thereof, said grate being spaced from said bar intermediate its ends and comprising longitudinal side bars and transverse grate-bars connecting said longitudinal side bars and spaced from one another, and a shaking-arm formed integrally with the strengthening-bar and extending above the same to provide a fuel-bearing surface, as set forth and bearing-bars 12 for supporting the same and end girder 12' for supporting outer end of bearing-bars 12 and center T-girder 14 for supporting inner end of bearing-bars 12, all substantially as set forth.

Signed at New York, in the county of New York and State of New York, this 24th day of January, A. D. 1901.

ELLIS F. EDGAR.
